[57] CLAIM

The ornamental design for a front panel for a room air conditioner, as shown.

DESCRIPTION

FIG. 1 is a frontal three-quarter perspective view of a front panel for a room air conditioner showing our new design, the broken line showing of the air conditioner cabinet being for illustrative purposes only and forming part of the claimed design;

FIG. 2 is a front elevational view thereof;

FIG. 3 is a top plan view thereof;

FIG. 4 is a bottom plan view thereof;

FIG. 5 is a right side elevational view thereof;

FIG. 6 is a left side elevational view thereof; and,

FIG. 7 is a rear elevational view of the front panel.
